UNITED STATES PATENT OFFICE.

HENRY M. CHEEK, OF FERNDALE, ARKANSAS.

AIR CONTROL.

1,341,260.

Specification of Letters Patent. Patented May 25, 1920.

Application filed July 30, 1919. Serial No. 314,196.

To all whom it may concern:

Be it known that I, HENRY M. CHEEK, a citizen of the United States, residing at Ferndale, in the county of Pulaski and State 5 of Arkansas, have invented a new and useful Air Control, of which the following is a specification.

It is the object of this invention to provide novel means for controlling the amount 10 of air admitted into the mixture of an internal combustion engine, and, in particular, the invention aims to provide novel means for regulating and mounting the valve which controls the air supply.

15 It is within the province of the disclosure to improve generally and to enhance the utility of devices of that type to which the invention appertains.

With the above and other objects in view, 20 which will appear as the description proceeds, the invention resides in the combination and arrangement of parts and in the details of construction hereinafter described and claimed, it being understood that, 25 within the scope of what is claimed, changes in the precise embodiment of the invention shown can be made without departing from the spirit of the invention.

In the accompanying drawings:—

30 Figure 1 shows in side elevation, a device constructed in accordance with the invention, parts being broken away; Fig. 2 is an end view of the valve; Fig. 3 is a longitudinal section, wherein parts appear in elevation; and Fig. 4 is a cross section taken approximately on the line 4—4 of Fig. 3.

The numeral 1 denotes the steering column of an automobile. A tube 2, which prefer- 40 ably is flexible, extends along the column 1 and is held upon the column by any desired number of clamps 3, of any selected construction. The tube 2 is held on the column 1, additionally, by a clamp 4 comprising op- 45 positively disposed members 5 having seats 6 adapted to receive the steering column 1 and provided with seats 7 coöperating to receive the tube 2. At their ends, and be- 50 tween the seats 6 and 7, the members 5 of the clamp are held together upon the column 1 and on the tube 2 by securing devices 8 of any desired sort. An arm 9 projects from the seat 7 of one member 5 of the clamp 4 and is disposed approximately parallel to 55 the steering column 1. A tubular casing 10 is secured at 25 to the arm

9, which arm is prolonged to form a resilient tongue or latch 19 terminating in a finger piece 20. The casing 10 is supplied at one end with a nipple 11 whereon one end of the tube 2 is mounted. The casing 10 is pro- 60 vided with a side port 12. A tubular valve 14 is threaded into the nipple 11 and is pro- vided with a side port 15 coöperating with the port 12 of the casing 10, the valve be- 65 ing closed at its outer end by a wall 16 pro- longed to form a marginal flange 17 having seats 18 wherein the tongue 19 is adapted to be received.

The tube 2 may lead to a carbureter, to an 70 intake manifold or to any other element of a like sort, for the purpose of allowing the admission of air into the mixture used in an internal combustion engine.

The tongue 19 may be sprung down- 75 wardly, by means of the finger piece 20 so that the tongue no longer is received in one of the seats 18 in the flange 17 of the tubular valve 14. When the tongue 19 thus is freed from the valve, the valve may be rotated and 80 because the valve is threaded into the casing 10, the valve may be advanced or retracted at will, thereby to move the port 15 into and out of registration with the port 12 in the casing 10. It will be obvious that the 85 entrance of air into the casing 10 and into the valve 14 may be regulated accurately, at the will of an operator, by the procedure above outlined. The air is delivered by the tube 2 to the carbureter, manifold or other 90 part of the engine. When the ports 15 and 12 have been located properly with respect to each other, the pressure on the finger piece 20 may be relieved, the tongue 19 be- 95 ing engaged in one of the seats 18, thereby to hold the valve against rotation and to hold the ports 15 and 12 in any relative position to which they have been adjusted.

The device forming the subject matter of this application is so constructed and so 100 mounted on the steering column 1, that the operator, without leaving his seat in the automobile, may at any time control the air delivered into the mixture.

It is to be observed that, in the device 105 shown and described, the air intake is always visible and accessible, and is air tight, when closed. The structure is positive in opera- 110 tion and may be worked readily from the driver's seat. Lost motion is avoided and there are no working parts widely remote from the initial point of force application.

Having thus described the invention, what is claimed is:—

In a device of the class described, a support; an air tube extended along the support; a clamp engaging the support and the tube and provided with an arm having a tongue; a casing carried by the arm and communicating with the tube; and a valve threaded into the casing, the casing and the valve having coöperating ports, the tongue

engaging the valve to hold the same against rotation.

In testimony that I claim the foregoing as my own, I have hereto affixed my signature in the presence of two witnesses.

HENRY M. CHEEK.
